United States Patent

Des. 236,897
Patented Sept. 23, 1975

236,897

COMPUTER CABINET

Robert M. Siegel, Los Angeles, F. Gordon Mackay,
Tarzana, and James J. Hall, Encino, Calif., assignors to
Xerox Corporation, Stamford, Conn.

Filed Oct. 9, 1973, Ser. No. 404,546

Term of patent 14 years

Int. Cl. D14—02

U.S. Cl. D26—5 C

FIG. 1

FIG. 3

FIG. 2

FIG. 4

FIG. 5

FIG. 6

FIG. 1 is a right perspective view of a computer cabinet showing our new design;

FIG. 2 is a front view thereof;

FIG. 3 is a rear view thereof;

FIG. 4 is a right side view thereof;

FIG. 5 is a left side view thereof; and

FIG. 6 is a top plan view thereof.

The grill-like pattern shown in FIG. 6 is understood to repeat throughout the indicated area.

We claim:

The ornamental design for a computer cabinet, as shown and described.
